UNITED STATES PATENT OFFICE.

EDMUND WRIGHT, OF PHILADELPHIA, PENNSYLVANIA.

DESIGN FOR A PARASOL.

SPECIFICATION forming part of Design No. 12,218, dated April 5, 1881.

Application filed February 14, 1881. Term of patent 3½ years.

To all whom it may concern:

Be it known that I, EDMUND WRIGHT, a citizen of the United States, residing in Philadelphia, Pennsylvania, have invented or produced a new and original Design for a Parasol, of which the following is a specification.

My design for a parasol-top is fully illustrated in the accompanying drawings, Figure 1 showing the parasol opened, and Fig. 2 showing the same closed.

The design comprises the rounded stud or button *a* in connection with the central projecting portion, *b*, or, as it is usually termed, the "canopy-top" of the parasol, the stud 15 forming a rounded continuation of said top in

place of the usual projecting end of the parasol-stick, and presenting a neat and attractive appearance.

I claim—

The design for a parasol-top, said design 20 comprising a rounded stud or button, *a*, forming a continuation of and finish for the canopy-top *b* of the parasol, as shown and described.

In testimony whereof I have signed my name to this specification in the presence of 25 two subscribing witnesses.

EDMUND WRIGHT.
